DISPLAY MANIKIN

Morris A. Wolf, 225 S. Los Angeles St.,
Los Angeles, Calif.

Filed Mar. 29, 1962, Ser. No. 69,475

Term of patent 14 years

(Cl. D80—8)

FIGURE 1 is a front perspective view of the display manikin showing my new design;

FIGURE 2 is a side elevational view thereof;

FIGURE 3 is a front elevational view thereof;

FIGURE 4 is a rear elevational view thereof; and

FIGURE 5 is a top plan view thereof.

I claim:

The ornamental design for a display manikin, substantially as shown.
